ROTARY-FINISHING MACHINE

BACKGROUND OF THE INVENTION

This invention pertains to rotary finishing machines for use in deburring, cleaning, polishing, and other finishing, of the type generally comprising a rotatable bowl adapted to contain a mass of abrasive finishing media, means for rotating the bowl, and spindle means for turning workpieces in the path of the mass of abrasive finishing media.

The bowl of a conventional machine of this type has a generally cylindrical wall and a generally circular bottom wall integral at its outer periphery with the lower periphery of the generally cylindrical wall. In at least a lower portion of the generally cylindrical wall, perforations are provided for screening the mass of abrasive finishing media so as to permit radially outward discharge of abrasive fines and other waste materials and retain the remainder of the charge or mass of abrasive finishing media within the bowl. Washing liquid, such as a solution of detergent in water, may be introduced into the bowl during rotation of the bowl through a spray head or the like. Such washing liquid helps to remove abrasive fines and other waste materials and is discharged through the perforations in the generally cylindrical wall of the bowl. Usually, the discharged matter is confined by an outer stationary protective housing and falls into a trough beneath from which it is carried to a drain. Such a housing also serves to protect the machine operator from injury caused by rotation of the bowl or discharge of matter from the bowl.

In a conventional machine of this type, the workpieces are held in suitable chucks or collets and are turned in the path of the mass of abrasive finishing media by suitable arranged rotatable spindles. Usually, from one to three workpieces are finished at one time in regularly spaced relationship in a generally annular useful work zone within the bowl. The abrasive finishing media may range in size from fine grits for use in polishing to heavy chips for use in heavy deburring and may be formed of any of a variety of natural, manufactured, and composite materials.

Conventionally, each spindle has a spindle housing, which is suitably supported within the bowl, and a spindle body, which is supported by and journaled within the spindle housing. Furthermore, each spindle forms part of spindle means additionally comprising a base or pedestal, a spindle arm supported by the base or pedestal above the bowl so as to extend generally radially inwardly with respect to the bowl, structure connected to the spindle arm supporting the spindle housing in a generally vertical position in the interior of the bowl, and a collet chuck adapted to releasably chuck workpieces to the lower end of the spindle body. Conventionally, a motor mounted to the spindle housing is used to rotate the spindle body within the spindle housing in such a manner as to turn workpieces held by the collet chuck in the path of the abrasive finishing media in the bowl.

It is desirable that the operator be able to adjust the position and orientation of the spindle in order to permit workpieces of varying sizes and shapes to be finished in varying amounts of abrasive finishing media. In previous rotary finishing machines of the type to which this invention pertains, it has been necessary to use either a manually operated jack screw or an overhead crane or the like to raise or lower the spindle, and other possible adjustments of the position and orientation are limited in applicability. Accordingly, there is a need for improvements in such rotary finishing machines whereby vertical, angular, and radial adjustments of the position and orientation of the spindle may be made easily and with minimal effort.

SUMMARY OF THE INVENTION

It is the principal object of this invention to provide an improved rotary finishing machine of the aforementioned type.

It is a more particular object of this invention to provide such a rotary finishing machine in which vertical, angular, and

radial adjustments of the position and orientation of the spindle may be made easily and with minimal effort.

It is another object of this invention to provide such a rotary finishing machine in which a motor is used to raise or lower the spindle.

It is a further object of this invention to provide a rotary finishing machine in which the same motor is used both to turn workpieces and to effect adjustments of the height of the spindle.

10 Other objects of this invention are to permit the orientation of the spindle housing with respect to the longitudinal axis of the spindle arm to be selectively adjusted and, furthermore, to permit the spindle arm to be selectively adjustable in extension.

15 The preceding objects may be attained in a rotary finishing machine of the type generally comprising a rotatable bowl adapted to contain a mass of abrasive finishing media, means for rotating the bowl, and spindle means for turning workpieces in the path of the mass of abrasive finishing media, in which the spindle means comprises a base or pedestal, a spindle arm supported by the base in such a manner as to normally extend generally radially inwardly with respect to the bowl, a spindle housing, a spindle body supported by and journaled to the spindle housing for turning movement within the spindle housing, support means supporting the spindle housing in such a manner as to permit longitudinal movement of the spindle housing along the axis of the spindle body, and a motor supported by the spindle housing and adapted to turn the spindle

20 25 30 35 body within the spindle housing. Preferably, the spindle means further comprises a releasable clamp, which is adapted to draw together portions of the support means against the spindle housing on opposite sides of an axial slot in the support means, and a collet chuck, which is operatively associated with the spindle body and is adapted to releasably chuck workpieces adjacent the lower end of the spindle body. The foregoing features are conventional in the spindle means of rotary finishing machines of this type.

In accordance with the principles of this invention, the spindle means further comprises means driven by the motor for selectively adjusting the position of the spindle housing with respect to the support means. Preferably, such means comprises an Acme thread or other thread formed along the spindle body in combination with a thread follower carried by the support means and movable through an axial slot in the spindle housing selectively into and out of engagement with the thread. Preferably, the motor which is used to turn the spindle body within the spindle housing is a reversible electric motor adapted to turn the spindle body selectively in either direction. Thus, the spindle may be raised, by engagement of the thread follower with the thread and subsequent operation of the motor in one direction, or lowered, by engagement of the thread follower with the thread and subsequent operation of the motor in the opposite direction. The same motor may be used to turn workpieces in the path of the abrasive finishing media upon disengagement of the thread follower from the thread and subsequent operation of the motor in either direction as desired.

60 It is a feature of a rotary finishing machine embodying the principles of this invention that the spindle means is connected to the spindle arm by structure comprising adjusting means for selectively adjusting the orientation of the spindle housing with respect to the longitudinal axis of the spindle arm.

65 Preferably, the adjusting means comprises means for selectively adjusting the orientation of the spindle housing in a plane which generally comprises the longitudinal axis of the spindle arm and means for selectively adjusting the orientation of the spindle housing in a plane which is substantially perpendicular to the longitudinal axis of the spindle arm.

70 75 It is another feature of such a rotary finishing machine that the spindle arm comprises outer and inner mutually telescoping members, one of the mutually telescoping members being supported by the base, the other being connected to the support means, in combination with means for selectively adjust-

ing the relative positions of the respective mutually telescoping members.

It is yet another feature of such a rotary finishing machine that the spindle arm may be pivotally mounted to the base for pivotal movement between an operative position wherein the spindle arm is extended radially inwardly with respect to the bowl and an inoperative position wherein the spindle arm is pivoted upwardly from the operative position. Preferably, the spindle arm is pivotally mounted to the base for pivotal movement about an axis of pivotal movement, preferably generally horizontal, which is oblique to a vertical plane comprising the axis of the spindle arm. In that instance, the spindle means preferably comprises moving means, such as fluid-driven cylinder mechanism, for selectively moving the spindle arm between the operative position and the inoperative position.

These and other objects, features, and advantages of this invention will be evident from the following description, with the aid of the attached drawings, of a preferred embodiment of this invention.

BRIEF DESCRIPTION OF THE DRAWINGS

In the drawings:

FIG. 1 is a side elevational view of a rotary finishing machine embodying the principles of this invention, showing a spindle in a raised position;

FIG. 2 is a top plan view of the rotary finishing machine of FIG. 1;

FIG. 3 is a partly broken away front elevational view of the rotary finishing machine of FIG. 1;

FIG. 4 is a sectional view, taken substantially along line 4—4 of FIG. 3 in the direction of the arrows;

FIG. 5 is a sectional view, on an enlarged scale, taken substantially along line 5—5 of FIG. 4 in the direction of the arrows, showing the spindle in a lowered position;

FIG. 6 is a sectional view, taken substantially along line 6—6 of FIG. 5 in the direction of the arrows;

FIG. 7 is a sectional view, taken substantially along line 7—7 of FIG. 3 in the direction of the arrows;

FIG. 8 is a sectional view, taken substantially along line 8—8 of FIG. 5 in the direction of the arrows;

FIG. 9 is a fragmentary front elevational view, also on an enlarged scale, of portions of the rotary finishing machine as shown in FIG. 3, showing the spindle in an intermediate position; and

FIG. 10 is a sectional view taken substantially along line 10—10 of FIG. 8 in the direction of the arrows.

DESCRIPTION OF THE PREFERRED EMBODIMENT

In the drawings, there is shown a rotary finishing machine 10 for use in deburring, cleaning, polishing, and other finishing. The rotary finishing machine 10, which constitutes a preferred embodiment of this invention, generally comprises a rotatable bowl 12 adapted to contain a mass of abrasive finishing media (not shown), means 14 for rotating the bowl, and spindle means 16 for turning workpieces in the path of the mass of abrasive finishing media during rotation of the bowl 12. A single spindle means 16 is shown in full throughout the drawings. In FIGS. 2 and 3, a second spindle means 16', similar to the spindle means 16, is shown diagrammatically for purposes to be explained hereinafter. Additional spindle means (not shown), similar to the spindle means 16 and 16', may be provided if desired. The plural spindle means 16, 16', etc. should be arranged in a regularly spaced relationship around the periphery of the bowl 12. Thus, a corresponding number of workpieces may be finished, at one time, in a regularly spaced relationship in a generally annular useful work zone within the bowl 12.

Means (not shown) may be provided for introducing washing liquid, such as a solution of detergent in water, into the bowl 12 during rotation of the bowl 12. Preferably, such means are in the form of conventional spray heads arranged to spray washing liquid onto the workpieces.

The bowl 12 comprises a generally cylindrical wall 18 and a generally circular bottom wall 20 integral with the wall 18. Preferably the wall 18 is provided with a plurality of removable screen panels (not shown) of the type disclosed in the copending application of Achille K. Ferrara, Ser. No. 800,387 filed Feb. 19, 1969 and assigned to the assignee of the present invention. Alternatively, a lower portion of the wall portion of the wall 18 itself may be provided with a multiplicity of uniform enlarged perforations, and screen cloth or the like of suitable mesh size may be wrapped around the perforated portion of the wall 18 and suitably fastened in place. The perforated screen panels, if used, or the perforated portion of the wall 18, if used, serves to screen the mass of abrasive finishing media so as to permit radially outward discharge of abrasive fines and retain the remainder of the mass of abrasive finishing media. Other waste materials and washing liquid are discharged with the abrasive fines.

The means 14 for rotating the bowl 12 is conventional and comprises an electric motor (not shown) and a right-angle speed reducer (not shown) preferably interconnected by means of a split-sheave variable-speed pulley system, indicated generally at 26, employing a V-belt 28.

The rotary finishing machine 10 further comprises an outer stationary protective housing 36 which serves to confine matter discharged from the bowl 12 during operation of the machine 10. The housing 36 also serves to protect the machine operator from injury caused by rotation of the bowl 12 or by discharge of matter from the bowl 12. The housing 36 defines a trough (not shown) to which matter discharged from the bowl 12 falls. The trough carries such matter to a drain (not shown). The housing 36 may be designed in multiple interfastened sections (not shown) so as to be capable of being disassembled to give access to the bowl 12.

Further details of the bowl 12, the means 14 for rotating the bowl 12, and the housing 36, as described in the preceding paragraphs, are beyond the scope of the present disclosure and may be supplied readily by those skilled in the art. Next to be described is the spindle means 16, which is constructed in accordance with the principles of this invention. It should be understood, that the spindle means 16' and any additional spindle means (not shown) are similarly constructed. As mentioned, the plural spindle means 16, 16', etc. should be arranged in a regularly spaced relationship around the periphery of the bowl 12.

As shown, the spindle means 16 comprises a spindle 40 and spindle supporting structure, indicated generally at 42. The spindle 40 is designed to turn workpieces in the path of the mass of abrasive finishing media contained in the bowl 12. The supporting structure 42 is designed to permit and facilitate vertical, angular, and rotary adjustments of the position of the spindle 40 with respect to the lateral and bottom walls of the bowl 12.

The spindle 40 generally comprises a spindle housing 44 and a spindle body 46 supported within and journaled to the spindle housing 44 for turning movement within the spindle housing 44. The spindle supporting structure 42 generally comprises a generally cylindrical base or pedestal 48, a spindle arm 50 supported by the base or pedestal 48 above the bowl 12 in such a manner as to normally extend generally radially inwardly with respect to the bowl 12, and support means 52 connected to the spindle arm 50 for supporting the spindle housing 44 in such a manner as to permit longitudinal movement of the spindle housing 44 along the axis of the spindle body 46. A motor 54, which is supported by the spindle housing 44, is adapted to turn the spindle body 46 within the spindle housing 44.

The spindle housing 44 comprises an elongated generally tubular member 60, which has a radially outwardly extending upper flange 62 and an elongated axial slot 66, lower bearing retaining structure 70, which is bolted or otherwise integrally attached to the flange 62, an outer wall member 72, which is bolted to the lower bearing supporting structure 70 by means of a plurality of bolts 74, upper bearing supporting structure

76, which is fastened to the outer wall member 72 by means of a plurality of bolts 78 (one shown), and bellows supporting structure 80, which is bolted or otherwise integrally attached to the upper bearing supporting structure 76. The spindle body 46 is in the form of an elongated generally tubular member 90, which is rotatably fitted within the spindle generally tubular member 60 and extends downwardly therefrom. A pulley 92 is mounted to the upper end portion 94 of the member 90 for conjoint rotation with the member 90. A worm gear 96 is mounted to the member 90, immediately beneath the pulley 92, for conjoint rotation with the member 90. The worm gear 96 has a lower hub portion 98 and an upper hub portion 100. The generally tubular member 90 of the spindle body 46 is rotatably fitted within and extends downwardly from the generally tubular member 60 of the spindle housing 44. The spindle body 46 is journaled to the spindle housing 44 by means of an upper rolling-contact thrust bearing 102 intermediate the lower hub portion 98 of the worm gear 96 and the upper bearing retaining structure 76 and a lower rolling-contact thrust bearing 104 intermediate the lower hub portion 100 of the worm gear 96 and the lower bearing retaining structure 70.

A worm-supporting shaft 110 is journaled to opposite sides (not numbered) of the outer wall member 72 of the spindle housing 44. A worm 112 is mounted to the shaft 110, in driving engagement with the worm gear 96, for conjoint rotation with the shaft 110. One end 114 (FIGS. 2 and 4) of the shaft 110 extends outwardly from the outer wall member 72 of the spindle housing 44, and a pulley 116 is mounted thereto for conjoint rotation with the shaft 110. The motor 54 is in the form of an intermittently operable reversible electric motor and is strapped or otherwise suitably mounted to a reinforced mounting bracket 118, which is welded or otherwise integrally attached to the outer wall member 72 of the spindle housing 44. The output shaft 120 (FIGS. 2 and 4) of the motor extends in spaced parallel relation to the worm supporting shaft 110. A pulley 122 is mounted to the output shaft 120 for conjoint rotation. An endless belt 124 is used to drive the pulley 116 from the pulley 122 in such a manner as to turn the spindle body 46 within the spindle housing 44. A conventional tachometer 126 having an input pulley 128 is mounted to the spindle housing 44 by means of a suitable bracket 130. An endless belt 132 is used to drive the pulley 128 of the tachometer 126 from the pulley 92 on the spindle body 46.

As shown, the support means 52 is in the form of a generally square columnar member 134 having a generally cylindrical opening 136 slidably receiving the spindle housing 44. Furthermore, as shown in FIGS. 8 and 9, the spindle housing 44 is slidably keyed to the support means by means of a key 138, which is seated in a suitable pocket 138a in the member 134 and is slidably in a suitable elongated groove 138b in the member 90.

In accordance with the principles of this invention, the spindle means 16 further comprises means 140 driven by the motor 54 for selectively adjusting the position of the spindle housing 44 with respect to the support means 52 along the axis of the spindle body 46. More particularly, the means 140 comprises a thread 142 which is formed along the spindle body 46, in combination with a thread follower 144, which is carried by the support means 52 and is movable through the axial slot 68 in the spindle housing 44 into and out of engagement with the thread 142. As shown, the thread 142 is an Acme thread, although other thread forms also would be suitable. The thread follower 144 comprises a half-nut 146 and a drawbolt 148. The half-nut 146 is slidably fitted in a suitably shaped slot 150 formed in the wall 152 of the support means 52. A plate 154 having a threaded opening 156 is welded or otherwise suitably attached to the wall 152 of the support means 52 at the margin of the slot 150. The drawbolt 148 has a threaded shank 158, which is threadably engaged with the threaded opening 156 in the plate 154, and an enlarged circular head 160, which is rotatably fitted in a circular socket 162 formed in the half-nut 146 and is held in place by means of a plate 164

having an unthreaded circular opening 166 for the shank 158. The plate 164 is rigidly fastened to the half-nut 146, preferably by means of machine screws (not shown). A hand wheel 168 is mounted to the shank 158 of the drawbolt 148, outwardly of the plate 154, for conjoint rotation with the drawbolt 148.

It is evident from the manner in which the aforesaid means 140 is constructed, that, upon engagement of the thread follower 144 with the thread 142, the spindle body 46 acts as a jackscrew with the result that rotation of the spindle body 46 within the spindle housing 44 by the motor 54, in the manner described hereinbefore, either raises or lowers the spindle housing 44 with respect to the support means 52 along the axis of the spindle body 46, depending on the direction of rotation of the spindle body 46 within the spindle housing 44. Because the motor 54 is in the form of a selectively reversible electric motor, as mentioned herebefore, the position of the spindle housing 44 with respect to the support means 52 may be selectively adjusted upwardly or downwardly, as desired.

The spindle means 16 further comprises means (not numbered) for releasably holding the spindle housing 44 in a selected position with respect to the support means 52. As shown, such means comprises a conventional releasable clamp 182 adapted to draw together portions of the support means 52 against the spindle housing 44 on opposite sides of an axial slot 184 in the support means 52. As shown, the clamp 182 is in the form of a flanged member 186 fastened to the support means 52 at one side of the slot 184 by means of machine screws 188 (FIGS. 9 and 10) and a flanged member 190 fastened to the support means 52 at the opposite side of the slot 184 by means of machine screws 192 (FIG. 10). The flanged members 186 and 190 are formed with aligned openings, 194 and 196 respectively. A bolt 198 passes through the aligned openings 194 and 196 and serves, when tightened, to draw together the portions of the support means 52 to which the respective flanged members 186 and 190 are fastened. When the bolt 198 is loosened, the position of the spindle housing 44 with respect to the support means 52 may be adjusted in the manner described hereinabove.

The spindle means 16 further comprises a conventional collet chuck 200 operatively associated with the spindle body 46 and adapted to releasably chuck workpieces to the spindle body 46 adjacent the lower end 202 of the spindle body. The collet chuck 200 comprises an adjusting sleeve 204, which is integrally connected to the lower end 202 of the spindle body 46 within an enlarged elongated axial socket 206 in the spindle body 46, and a gripping member 208, which is movable axially with respect to the spindle body 46 within the adjusting sleeve 204. As shown, the adjusting sleeve 204 has a radially outwardly extending flange 210 and an outwardly opening conical camming surface 212 and is integrally connected to the lower end 202 of the spindle body 46 by means of an internally threaded collar 214 threadably engaging a suitably threaded end portion 216 of the spindle body 46. The collar 214 has a radially inwardly extending flange 218 adapted to hold the flange 210 of the adjusting sleeve 204 against the end surface 220 of the spindle body 46. The gripping member 208, which is generally tubular, as shown, has an externally threaded end portion 220 and is axially slotted in such a manner as to form a plurality of axially extending finger portions 222, as is known. The gripping member 208 should be made of spring steel or other inherently resilient material, as is known. The respective finger portions 222 of the gripping member 208 have outer conical camming surfaces 224 corresponding to the camming surface 212 of the adjusting sleeve 204. The threaded end portion of the gripping member 208 is threadably connected to a suitably threaded axial socket 226 in a guiding member 228, which is slidably fitted within the axial socket 206 in the spindle body 46 above the adjusting sleeve 204. The guiding member 228 is permitted a limited amount of axial movement within the axial socket 206 in the spindle body 46. Thus, the gripping member 208 is movable axially with respect to the spindle body 46 between a retracted

position and an extended position, as mentioned hereinbefore. As the gripping member 208 is moved from the extended position toward the retracted position, the camming surfaces 208 of the respective finger portions 222 of the gripping member 208 are drawn against the camming surface 212 of the adjusting sleeve 204 in such a manner as to bend the finger portions 222 radially inwardly. Thus, in the retracted position of the gripping member 208, the finger portions 222 are radially contracted, and, in the extended position of the gripping member 208, the finger portions 222 are radially expanded.

The collet chuck 200 further comprises a push rod 230, which extends through an axial bore 232 in the spindle body 46 and is connected to the gripping member 208, biasing means 234 acting on the push rod 230 to bias the gripping member 208 to the retracted position, and actuating means 236 arranged to act on the push rod 230 in opposition to the biasing means 234 to move the gripping member 208 to the extended position. The push rod 230 is guided within upper and lower sleeve bearings, 238 and 240 respectively, which preferably are formed in one piece with the spindle body 46, and is connected to the gripping member 208 by means of a capscrew 242, which passes through an axial opening 244 in the guide member 228 and threadably engages a suitably threaded axial socket 246 in the lower end 248 of the push rod 230. An elongated stud 250 threadably engages a suitably threaded axial socket 246 in the upper end 252 of the push rod 230 and serves as an axial extension of the push rod 230. The stud 250 is held in place by means of a nut 254 and extends upwardly through an opening 256 in the aforementioned bellows supporting structure 80. A plate 258 having an upwardly turned lateral flange 260 and an opening 262 for the stud 250 is fastened to the bellows supporting structure 80 by means of capscrews 264. The stud 250 passes freely upwardly through the opening 262 in the plate 260. A cover member 270, which has a circular top wall 272 and a downwardly extending cylindrical wall 274, is welded or otherwise rigidly attached to the upper end 276 of the stud 250. The biasing means 234 is in the form of a helical spring 278 between the plate 260 and the top wall 272 of the cover member 270. The plate 260 forms part of bellows housing structure 284, which further comprises a cover member 286 having a top wall 288 provided with a nipple 290 and having a downwardly extending generally cylindrical wall 292 welded or otherwise rigidly attached to the flange 262 of the plate 260. A flexible bellows 294 is suitably fastened within the cover member 286 of the bellows housing structure 284 and is disposed in generally contiguous relation to the cover member 270 on the stud 250. The bellows 294 may be pressurized or depressurized, through the nipple 290, by conventional pneumatic means (not shown). When the bellows 294 is pressurized, the push rod 230 is driven downwardly against the bias imposed by the spring 278 and the collet member 208 is moved to the extended position. When the bellows 294 is depressurized, the collet member 208 is restored to the retracted position by the spring 278. Also, when the bellows 294 is depressurized, there is sufficient clearance between the bellows 294 and the cover member 270 on the stud 250 for the cover member 270 to turn freely with respect to the bellows 294. As is evident, the cover member 270 turns conjointly with the spindle body 46.

Herein a longitudinal axis taken through the radial center of the arm 50 is considered to be the "longitudinal axis" of the spindle arm 50. In accordance with the principles of this invention, the spindle means 16 further comprises adjusting means (not numbered) for selectively adjusting the orientation of the spindle body 46 with respect to the longitudinal axis of the spindle arm 50. The orientation of the spindle body 46 is defined by the orientation of the longitudinal axis of the spindle body 46. More particularly, the adjusting means comprises means 302 for selectively adjusting the orientation of the spindle body 46 in a plane which generally comprises the longitudinal axis of the spindle arm 50 and means 304 for selectively adjusting the orientation of the spindle body 46 in a plane which is substantially perpendicular to the longitudinal axis of the spindle arm 50.

The means 302 for selectively adjusting the orientation of the spindle body 46 in a plane which generally comprises the longitudinal axis of the spindle arm 50 comprises a bracket 310 having an outer wall 312 and opposite sidewalls 314 and 316. An outwardly directed stub shaft 318 extends outwardly through an opening 320 in the outer wall 312 and is welded or otherwise suitably integrally attached to the outer wall 312 at an inner flange or boss 322. An inwardly directed stub shaft 324, which is slightly smaller in diameter than the stub shaft 318, extends inwardly through an opening 326 in the sidewall 314 and is welded or otherwise integrally attached to the sidewall 314 at an outer flange or boss 328. A similar stub shaft 330, which is axially aligned with the stub shaft 324, extends inwardly through an opening 332 in the sidewall 316 and is welded or otherwise integrally attached to the sidewall 316 at an outer flange or boss 334.

The stub shaft 318 is aligned with the spindle arm 50 and is connected thereto in a manner to be described hereinafter. The stub shaft 324 passes through an annular spacer 336 between the wall 314 of the bracket 310 and the support means 52. The stub shafts 324 and 326 are rotatably fitted into aligned openings, 338 and 340 respectively, on opposite sides of the support means 52 and pivotally support the support means 52 in such a manner as to permit pivotal movement of the support means 52 upon the axis of pivotal movement defined by the stub shafts 324 and 326. Such movement of the support means 52 produces changes in the orientation of the spindle body 46 in a plane which generally comprises the longitudinal axis of the spindle arm 50, that is, in a plane which either is in closely spaced substantially parallel relation to the longitudinal axis of the spindle arm 50 or, as shown, actually comprises the longitudinal axis of the spindle arm 50.

The sidewall 314 of the bracket 310 has spaced downwardly extending legs 352. The aforesaid means 302 further comprises a shaft 354 (FIG. 10), which is journaled in openings 356 (one shown) in protruding generally annular lug portions 358 (one shown) in protruding generally annular lug portions 358 (one shown) of the respective legs 353, a hand wheel 360, which is suitably fastened to the shaft 354 for conjoint rotation, and a partial worm gear 364, which engages the worm 362 and is rigidly mounted to the support means 52 by means of a plurality of capscrews 366. As shown, a crank handle 368 is operatively mounted to the hand wheel 360. Rotation of the hand wheel 360 produces pivotal movement of the support means 52 upon the axis of pivotal movement defined by the stub shafts 324 and 326 and thus produces the desired component of adjustment of the orientation of the spindle body 46 with respect to the longitudinal axis of the spindle arm 50.

The stub shaft 318 is rotatably fitted within an elongated generally tubular member 380, which forms part of the spindle arm 50 and is keyed to the generally tubular member 380 for rotation therewith by means of a plurality of studs 382 having threaded heads 384 and radially inwardly extending shanks 386. The heads 384 of the respective studs 382 fit into an annular groove 390 formed in the stub shaft 318, which thereby is permitted to rotate within the generally tubular member 380 yet is prevented from moving axially with respect to the generally tubular member 380. Consequently, the bracket 310 is permitted pivotal movement about the longitudinal axis of the stub shaft 318 and thus about the longitudinal axis of the spindle arm 50. Such movement of the bracket 310 produces changes in the orientation of the spindle body 46 substantially in rotation about the longitudinal axis of the spindle arm 50.

The means 304 for selectively adjusting the orientation of the spindle body 46 in a plane which is substantially perpendicular to the longitudinal axis of the spindle arm 50 comprises a generally annular bracket 390, which has spaced downwardly extending legs 392 and is welded or otherwise integrally attached to the generally tubular member 380 in spaced relation to the outer wall 312 of the bracket 310, a shaft 394, which is journaled in openings 396 (one shown) in protruding generally annular lug portions 398 of the respective legs 392, a hand wheel 400, which is suitably fastened to

the shaft 394, a worm 402, which is mounted on the shaft 394 for conjoint rotation, and a partial worm gear 404, which engages the worm 402 and is rigidly mounted to the outer wall 312 of the bracket 310 by means of a plurality of capscrews 406. As shown, a crank handle 408 is operatively mounted to the hand wheel 400. Rotation of the hand wheel 400 produces pivotal movement of the bracket 310 about the longitudinal axis of the spindle arm 50 and thus produces the desired component of adjustment of the orientation of the spindle body 46 with respect to the longitudinal axis of the spindle arm 50.

Because adjustment of the orientation of the spindle body 46 with respect to the longitudinal axis of the spindle arm 50 does not require lifting of any heavy components, the hand wheel 360 and the hand wheel 400 operate satisfactorily. However, for added convenience, either the worm 362 otherwise driven by the hand wheel 360 or the worm 402 otherwise driven by the hand wheel 400, or both conjointly or separately, may be arranged to be driven in either direction by means of an intermittently operable reversible electric motor (not shown) or the like, details of which may be supplied readily by those skilled in the art.

The spindle arm 50 comprises outer and inner mutually telescoping members, a sleeve member 420 and the aforesaid elongated generally tubular member 380 respectively, and means 422 for adjusting the position of the generally tubular member 380 with respect to the sleeve member 420. The generally tubular member 380 has an axial slot 424 therein and extends through the sleeve member 420, which is substantially shorter than the generally tubular member 380, for telescoping movement within the sleeve member 380. The aforesaid means 422 comprises an elongated externally threaded screw member 426, which is journaled within the generally tubular member 380 in parallel relation to the axial slot 424, a screw follower 432, which is slidably within the generally tubular member 380 and is threadably engaged with the screw member 426, and means 434 which is supported by the sleeve member 420 and is extended through the axial slot 424 in sliding relation to the generally tubular member 380 for holding the screw follower 432 in fixed relation to the sleeve member 420 upon rotation of the screw member 426 with respect to the generally tubular member 380. The screw member 426 has an unthreaded shank portion 436. A thrust bearing 438 is threadably connected to a suitably threaded end portion 440 of the generally tubular member 380. The shank portion 436 of the screw member 426 is journaled in the thrust bearing 438. A hand wheel 442 is suitably fastened to the shank portion 436 of the screw member 426, and, as shown, a crank handle 444 is operatively mounted to the hand wheel 442. Preferably, the screw member 426 is formed with a ball thread 446, as shown, and the screw follower 432 is in the form of a ball nut 448 having a corresponding thread (not shown). Preferably, the aforesaid means 434 is in the form of a stud 450 having a threaded head 452, which is threadably connected to the sleeve member 420 in a suitably threaded opening 454, and having a shank 456, which is extended radially inwardly through the axial slot 424 and is seated in a suitably formed socket 458 in the ball nut 448. The stud 450 prevents both rotation and axial movement of the ball nut 448 with respect to the sleeve member 420.

The shank 456 of the stud 450 cooperates with the margins of the axial slot 424 in such a manner as to permit axial movement of the generally tubular member 380 with respect to the sleeve member 420 yet prevent rotation of the generally tubular member 380 with respect to the sleeve member 420. Rotation of the hand wheel 442 produces adjustment of the axial position of the generally tubular member 380 with respect to the sleeve member 420.

Because adjustment of the axial position of the generally tubular member 380 with respect to the sleeve member 420 does not require lifting of any heavy components, the hand wheel 442 operates satisfactorily. However, for added convenience, the screw member 426 may be arranged to be selec-

tively driven in either direction by means of an intermittently operable reversible electric motor (not shown) or the like, details of which may be supplied readily by those skilled in the art.

5 The spindle arm 50 is pivotally mounted to the base or pedestal 48 for pivotal movement between an operative position and an inoperative position. In the operative position, the spindle arm 50 is extended radially inwardly with respect to the bowl 12. In the inoperative position, the spindle arm 50 is elevated from the operative position.

More particularly, spindle arm 50 is pivotally mounted to the base or pedestal 48 for pivotal movement about an axis of pivotal movement oblique to a vertical plane which comprises the longitudinal axis of the spindle arm 50. Preferably, the axis of pivotal movement of the spindle arm 50 with respect to the base or pedestal 48 is horizontal and is orientated at an angle of approximately 45° with respect to a vertical plane which comprises the longitudinal axis of the spindle arm 50. Consequently, pivotal movement of the spindle arm 50 from the operative position draws a workpiece which is held by the aforesaid collet chuck 200 upwardly and outwardly from the bowl 12. This is illustrated in FIG. 3, wherein movement of the spindle means 16' from its operative position to its inoperative position is illustrated diagrammatically. Also see FIG. 2, in which the spindle means 16' is shown diagrammatically in its inoperative position.

20 The sleeve member 420 of the spindle arm 50 is pivotally supported on the base or pedestal 48 by means of opposite stub shafts, 460 and 462 respectively, which are welded or otherwise integrally mounted to the sleeve member 420 in such a manner as to define an axis of pivotal movement of the spindle arm 50 which is oriented as desired. The stub shaft 460 is suitably journaled to an upright arm 468 which is welded or otherwise rigidly attached to the base or pedestal 48. The stub shaft 462 is similarly journaled to an upright arm 470, which is welded or otherwise rigidly attached to the base or pedestal 48 in diametrically opposite relation to the arm 468. As shown in FIG. 3, the base or pedestal 48 is formed with an integral rest 30 472, which is adapted to support the sleeve member 420 and thus the spindle arm 50 when the spindle arm 50 is in the operative position, and is cut away, as indicated at 474, in order to permit the spindle arm 50 to be pivoted from the operative position to the inoperative position. Owing to the 35 distribution of weight inherent in the structure of the spindle means 16, the spindle arm 50 is stable in the operative position.

40 The spindle means 16 further comprises moving means 480 for selectively moving the spindle arm 50 between the operative position and the inoperative position. As shown, the moving means 480 comprises fluid-driven cylinder mechanism 482 intermediate the spindle arm 50 and the base or pedestal 48. The mechanism 482 may be either pneumatic or hydraulic, the former being preferred, and, as shown, comprises a cylinder case 484, which is pivotally connected to the base or pedestal 48, and an extensible retractable rod 486, which is pivotally connected to the spindle arm 50. A bracket 488 is welded or otherwise rigidly connected to the base or pedestal 48.

45 A clevis 490 is suitably integrally attached to the lower end 492 of the cylinder case 484 and is pivotally connected to the bracket 488 at a pinned connection 494. A crank arm 496 is welded or otherwise rigidly connected to the sleeve member 420 in such a manner as to extend upwardly and outwardly in generally perpendicular relation to the axis of pivotal movement of the spindle arm 50. A clevis 498 is suitably integrally attached to the upper end 500 of the rod 486 and is pivotally connected to the crank arm 496 at a pinned connection 502. pressure. Inherent damping in the mechanism 482 permits the spindle arm 50 to drop slowly to the operative position upon release of fluid pressure.

Modifications and improvements within the scope of this invention may be suggested by this disclosure to those skilled in the art. Accordingly, the scope of this invention should be determined from the following claims.

We claim:

1. A rotary finishing machine comprising a rotatable bowl adapted to contain a mass of abrasive finishing media, means for rotating said bowl, and spindle means for turning work-pieces in the path of said mass of abrasive finishing media during rotation of said bowl, said spindle means comprising a base, a spindle arm supported by said base above said bowl in such a manner as to normally extend generally radially inwardly with respect to said bowl, a spindle housing, a spindle body supported within and journaled to said spindle housing for turning movement within said spindle housing, support means connected to said spindle arm for supporting said spindle housing in such a manner as to permit movement of said spindle housing with respect to said support means along the axis of said spindle body, a motor supported by said spindle housing and adapted to turn said spindle body within said spindle housing, and means driven by said motor for selectively adjusting the position of said spindle housing with respect to said support means along the axis of said spindle body.

2. The rotary finishing means of claim 1 wherein said means for selectively adjusting the position of said spindle housing axially with respect to said support means along the axis of said spindle body comprises a thread, which is formed along said spindle body, and a thread follower, which is carried by said support means and is movable through an axial slot in said spindle housing selectively into and out of engagement with said thread.

3. The rotary finishing machine of claim 2 wherein said thread is an Acme thread.

4. The rotary finishing machine of claim 2 wherein said thread follower comprises a half-nut, which is slidably fitted in a slot formed in said support means, and a drawbolt, which is adapted to draw said half-nut within said slot selectively into and out of engagement with said thread.

5. The rotary finishing machine of claim 2 wherein said motor is in the form of a selectively reversible electric motor supported by said spindle housing for movement therewith.

6. The rotary finishing machine of claim 2 wherein said spindle means further comprises means for releasably holding said spindle housing in a selected position with respect to said support means.

7. The rotary finishing machine of claim 6 wherein said means for releasably holding said spindle housing in a selected position with respect to said support means comprises a releasable clamp adapted to draw together portions of said support means against said spindle housing on opposite sides of an axial slot in said support means.

8. The rotary finishing machine of claim 1 wherein said spindle means further comprises a collet chuck operatively associated with said spindle body and adapted to releasably chuck workpieces to said spindle body adjacent the lower end of said spindle body.

9. The rotary finishing machine of claim 1 wherein said spindle arm has a longitudinal axis and said support means is connected to said spindle arm by structure comprising adjusting means for selectively adjusting the orientation of said spindle body with respect to the longitudinal axis of said spindle arm.

10. The rotary finishing machine of claim 9 wherein said adjusting means comprises means for selectively adjusting the orientation of said spindle body in a plane which generally comprises the longitudinal axis of said spindle arm.

11. The rotary finishing machine of claim 9 wherein said adjusting means comprises means for selectively adjusting the orientation of said spindle body in a plane which is substantially perpendicular to the longitudinal axis of said spindle arm.

12. The rotary finishing machine of claim 9 wherein said adjusting means comprises means for selectively adjusting the orientation of said spindle housing in a plane which generally comprises the longitudinal axis of said spindle arm and means for selectively adjusting the orientation of said spindle housing in a plane which is substantially perpendicular to the longitudinal axis of said spindle arm.

13. The rotary finishing machine of claim 1 wherein said spindle arm comprises outer and inner mutually telescoping members, one of said mutually telescoping members being supported by said base, the other of said mutually telescoping members being connected to said support means.

14. The rotary finishing machine of claim 13 further comprising means for selectively adjusting the axial position of said other of said mutually telescoping members with respect to said one of said mutually telescoping members.

15. The rotary finishing machine of claim 14 wherein said inner mutually telescoping member is elongated and generally tubular and has an axial slot formed therein, and wherein said means for selectively adjusting the axial position of said other of said mutually telescoping members with respect to said one of said mutually telescoping members comprises an elongated externally threaded screw member journaled within said generally tubular member in parallel relation to said axial slot,

20 a screw follower slidable within said inner mutually telescoping member and threadably engaged with said screw member, and means supported by said outer mutually telescoping member and extended through said axial slot is sliding relation to said inner mutually telescoping member for holding said screw follower in fixed relation to said outer mutually telescoping member upon rotation of said screw member with respect to said inner mutually telescoping member.

16. The rotary finishing machine of claim 13 wherein said outer mutually telescoping member is supported by said base and said inner mutually telescoping member is connected to said support means.

17. The rotary finishing machine of claim 16 further comprising means for selectively adjusting the axial position of said inner mutually telescoping member with respect to said outer mutually telescoping member.

18. The rotary finishing machine of claim 17 wherein said inner mutually telescoping member is elongated and generally tubular and has an axial slot formed therein, and wherein said means for selectively adjusting the axial position of said inner mutually telescoping member with respect to said outer mutually telescoping member comprises an elongated externally threaded screw member journaled within said inner mutually telescoping member in parallel relation to said axial slot, a screw follower slidable within said inner mutually telescoping member and threadably engaged with said screw member, and means supported by said outer mutually telescoping section and extended through said axial slot in sliding relation to said inner mutually telescoping member for holding said screw follower in fixed relation to said outer mutually telescoping member upon rotation of said screw member with respect to said inner mutually telescoping member.

19. The rotary finishing machine of claim 1 in which said spindle arm is pivotally mounted to said base for pivotal movement between an operative position wherein said spindle arm is extended radially inwardly with respect to said bowl and an inoperative position wherein said spindle arm is pivoted upwardly from said operative position.

20. The rotary finishing machine of claim 19 wherein said spindle arm has an axis and is pivotally mounted to said base for pivotal movement about an axis of pivotal movement oblique to a vertical plane which comprises the axis of said spindle arm.

21. The rotary finishing machine of claim 20 wherein the axis of pivotal movement of said spindle arm is generally horizontal.

22. The rotary finishing machine of claim 19 wherein said base provides an integral rest for said spindle arm in said operative position and said spindle arm is stable in said operative position.

13

23. The rotary finishing machine of claim 19 wherein said spindle means further comprises moving means for selectively moving said spindle arm between said operative position and said inoperative position.

24. The rotary finishing machine of claim 23 wherein said moving means comprises fluid-driven cylinder mechanism arranged to move said spindle arm from said operative position.

25. The rotary finishing machine of claim 24 wherein said

14

fluid-driven cylinder mechanism comprises a cylinder case pivotally connected to said base and an extensible-retractable rod pivotally connected to said spindle arm.

26. The rotary finishing machine of claim 25 wherein said extensible-retractable rod is pivotally connected to said spindle arm through a crank arm integrally mounted to said spindle arm.
